UNITED STATES PATENT OFFICE.

WILLIAM E. WINE, OF TOLEDO, OHIO.

DOOR MECHANISM FOR RAILWAY CARS.

Application filed June 8, 1923. Serial No. 844,140.

To all whom it may concern:

Be it known that I, WILLIAM E. WINE, a citizen of the United States, residing at Toledo, in the county of Lucas and State of Ohio, have invented certain new and useful Improvements in Door Mechanism for Railway Cars; and I do hereby declare the following to be a full, clear, and exact description of the invention, such as will enable others skilled in the art to which it appertains to make and use the same.

My invention relates to door mechanism for railway cars and has for its objects, among others, to provide improved features of door construction, to afford an advantageous arrangement of door arms for maintaining the door in closed position, and to provide improved means for enabling the door to be forced to fully closed position by means of a removable lever or prying bar.

A primary feature of the invention, generally stated, consists in providing the hinged door of a railway car with a marginal flange bordering its free edge, and in rigidly securing to said flange in overlapping relation a flanged member having an inwardly extending portion disposed parallel to the plane of the door and spaced therefrom, the door having secured thereto a plurality of door supporting arms passing beneath and having engagement with the said flanged member, and movable means, preferably formed as hooks, being mounted upon the car body for cooperating with the door arms to support the door in closed position.

Another feature of the invention consists in securing to the hinged door of a railway car a plurality of door supporting arms which extend obliquely to the hinge axis of the door, said arms being convergent outwardly and having portions which project beyond the free edge of the door for cooperation with door supporting hooks movably mounted upon the car body.

A still further feature of the invention consists in providing the hinged door of a railway car with a central stiffener which terminates at its outer end adjacent the free edge of the door, and in securing to said door upon opposite sides of said stiffener, a plurality of door arms whose outer ends project beyond the door so as to cooperate with supporting hooks pivotally mounted upon the car body, the door also being provided with means constituting a lever seat located at the outer end of the door stiffener, and the car body being furnished with means forming a fulcrum for cooperating with a removable lever adapted to engage the said lever seat of the door to force the door to closed position.

As will hereinafter appear, there are other features of the invention residing in special relations of parts and in advantageous details of construction.

In the drawings chosen for the purpose of illustrating the preferred mode of applying the principle of the invention, the scope whereof is pointed out in the claims:

Figure 1 is a horizontal section of a portion of a car showing door mechanism embodying the invention.

Figure 2 is a detail view in side elevation of the portion of the car illustrated in Figure 1.

Figure 3 is a detail section on the line 3—3 of Figure 2, an open position of the hinged door and the car clearance line, which is designated by the reference letter A, being indicated in dotted lines.

The car illustrated in the drawings will be recognized as of the gondola type but it is to be understood that the invention claimed is not limited to cars of that character. The side 1 of the car may advantageously be formed of a steel plate having a bottom flange angle 2 secured along the lower edge thereof by means of rivets 3. The angle iron 2 engages the inner face of the side sheet of the car and its horizontal leg extends inwardly. Any desired center sill construction may be employed in the car, such for example as the customary center sill channels 4 and their connecting cover plate 5. Diaphragms or cross bearers 6, preferably flanged and formed of pressed metal, may advantageously extend from the adjacent center sill outwardly to the side of the car where they are riveted to the lower ends of side stakes 7 which are secured to the car side and whose lower ends project downwardly beyond the lower edge of the side plate 1. Between adjacent diaphragms 6 a door opening is formed in the floor of the car; in some cars a plurality of such openings is provided. In the present exemplification of my invention the outer edge 8 of the door opening is defined by the inner edge of the horizontal leg of the flange angle 2 bordering the lower edge 9 of the side plate of the car; the inner edge 9 of the door opening is defined by the edge

of the cover plate 5; and the sides 10 of the door opening are defined by the adjacent edges of the diaphragm cover plates 11. It will thus be seen that in cars where a plurality of doors is desired, the entire car floor in the vicinity of the doors may be constituted by the cover plate 5 of the center sills, the diaphragm cover plates 11, and the horizontal legs of the bottom flange angles 2. While the drawings only illustrate a portion of the car lying upon one side of its center line, it is to be understood that the same features of construction are incorporated in the portion of the car lying upon the opposite side of the center line.

The door openings are closed by hinged doors 12. Each of these doors is preferably constructed from a steel plate formed with a down-turned marginal flange 14 at its hinged edge and with a down-turned marginal flange 14 bordering the free edge of the door remote from the hinge axis. The hinging of the door may be advantageously effected by means of suitable cooperating body hinges 15 and door hinges 16, which are pivotally connected by a hinge pintle 17 extending longitudinally of the car, the hinge axis being preferably positioned in close proximity to the neighboring edge 30 of the center sill cover plate 5. The body hinges 15 may be secured by rivets to the outer faces of the respectively corresponding center sill channels 4, while the door hinges 16 may be attached to the door by means of rivets through the intervention of flanged door stiffening members 18. In the present construction three sets of hinges are employed, one set being located at each side of the door and the third set being positioned approximately midway between the two side hinges.

The stiffening members 18 extending from the side hinges along the respective side edges of the door are preferably of channel form, the upper flange of the channel being of somewhat greater width than the lower flange, and said upper flange being in engagement with the undersurface of the door and being secured thereto by rivets passing through the door plate. The door is also provided with an intermediate stiffener 19 extending from the central hinge outwardly and terminating adjacent the marginal flange 14 at the free edge of the door remote from the hinge axis. This centrally disposed stiffener is preferably formed as an angle iron whose horizontal flange is riveted to the door plate. The rear ends of the stiffeners 18 and 19 are preferably interposed between the door plate and the door hinge members and these several parts may be respectively connected by common rivets.

For the purpose of further stiffening the free edge of the door remote from the hinge axis and to afford supporting seats or bear-

ings for the door arms, as well as to provide a lever seat for cooperating with a removable door prying lever, a flanged member 20 is secured to the door in parallel relation to the marginal door flange 14. The flange 70 stiffening member 20 may be in the form of an angle iron whose vertical leg overlaps and is riveted to the door flange 14, and whose horizontal leg extends inwardly in parallel spaced relation to the plane of the door 12. The flanged member 20 is preferably of sufficient length to extend substantially the full width of the door so as to overlap the stiffening members 18. The horizontal leg of the angle iron 20 thus provides, as will hereinafter appear, an effective and substantial lever seat near the outer end of the intermediate door stiffener 19, and it also provides efficient bearings or seats for the door arms through which the 80 door is maintained in closed position by pivoted hooks mounted upon the side of the car. The door arms 21 preferably are flanged members and may advantageously be of angle iron form. Their rear ends engage and are rigidly secured to the respective door stiffening members 18 at the sides of the door 12. From their points of attachment to the door stiffeners 18 the arms 21 extend obliquely outward and pass beneath the horizontal flange of the angle iron 20 and beneath the marginal flange 14 at the free edge of the door. The door arms 21 are bent or inclined downwardly sufficiently to bring their upper flanges into 90 abutting engagement with the horizontal leg of the flanged member 20, rivets 22 being employed for securing said arms to said member 20. The outer ends 23 of the angle iron door arms project outwardly beyond the 105 plane of the side plate 1 so as to constitute locking faces or seats for cooperating with door supporting members pivotally mounted upon the outer face of the car side. The projecting outer ends 23 of the door arm 110 angle irons 21 are preferably disposed horizontally and maintain the same oblique direction as the adjacent portions of the arms which are immediately beneath the door. The inclination of the door arms 21 with respect to each other is such that they converge outwardly, thus causing their outer ends 23 to be closer together than are their rear ends and thereby spacing the outer ends of the arms at a substantial distance 115 from the side edges of the door and at a correspondingly less distance from the central door stiffener 19 and the lever seat adjacent thereto.

The means for cooperating with the door 125 arms 21 to support the door in closed position preferably comprise hooks 24 of a type now well known. These hooks are pivoted upon rivets 25 and are mounted upon the side of the car by means of brackets 26. 130

Pivoted locking cams 27 may be employed to maintain the respective hooks 24 in locked position. The hooks are preferably arranged to swing in planes parallel with the outer face of the car side so as to engage the outer ends of the door arms 21 at a relatively short distance from the free edge of the door.

When a door of this character is designed to be lifted by hand to a preliminary position in which the door is not entirely closed, it is desirable to provide means for forcing it to a final position of closure. To support the door temporarily in an approximately closed position, the supporting hooks 24 are, as shown, commonly provided with auxiliary supporting ledges 28^a in addition to ledges 28 for cooperating with the outer ends 23 of the door arms to maintain the door entirely closed. The forcing of the door from its partly closed position to a fully closed position is now commonly effected by employing a removable lever or prying bar. To cooperate with such a lever a fulcrum plate 29 having a hole 30 through which the end of the lever or bar (not shown) may be inserted, is rigidly secured to the outer face of the car side between the hooks 24 adjacent to and preferably in alinement with the centrally disposed door stiffener 19. The fulcrum plate 29 thus permits the rear end of the door prying lever to be brought into engagement with the horizontal leg of the stiffening angle 20 at the outer end of the intermediate stiffening member 19 of the door, thus enabling the prying force applied to close the door to be resisted and distributed by both door stiffening members 19 and 20 as well as by the door flange 14. The prying force applied to the door by the removable lever is in great measure efficiently transmitted to the door arms 21 by the marginal flange 14 and the adjacent angle iron 20 secured thereto, thereby enabling the outer ends 23 of the door arms to be readily forced upwardly to positions where they may be seated upon the upper ledges 28 of the supporting hooks. The facility with which the final closing operation of the door may be effected is also contributed to by the fact that the bearings of the door arms upon the flanged member 20 at the free edge of the door are somewhat removed from the side edges of the door and are not far distant from the point on the door to which the prying force of the lever is applied, since such an arrangement reduces the bending or spring of the parts. Not only is this arrangement of parts advantageous during the operation of forcing the door to fully closed position, but it also results in a disposition of the supporting hooks at points removed from the side edges of the door and thus results in decreasing the

amount of yielding or springing of the door and the bending stresses to which it is subjected. By disposing the door arms so that they diverge from the free edge of the door, toward the hinge axis of the latter, the door resists the load upon it in an efficient manner; and in that the door arms converge towards their outer ends the load upon the door is communicated to the car side in an advantageous way. The entire mechanism is tied together and braced so as to provide a practical door construction for use with hooks pivotally mounted upon the car side and all parts of the mechanism in whatever positions they may assume are well within the clearance line A of the car.

I claim:

1. In car door mechanism, the combination with a hinged door provided with a marginal flange, of a flanged member rigidly secured to said door and overlappingly engaging the marginal flange thereof, one of the flanges of said flanged member being disposed at an angle to the said door flange, an arm secured to said door and projecting outwardly beyond the said flanged member and door flange, said arm passing beneath and having engagement with the flange of said flanged member which is angularly disposed with respect to the marginal flange of the door, and means movably mounted upon the car body for cooperating with said arm to support said door in closed position.

2. In car door mechanism, the combination with a hinged door provided with a marginal flange bordering the free edge thereof opposite its hinged edge, of a flanged member rigidly secured to said door and extending parallel to said marginal flange in overlapping relation therewith, one of the flanges of said flanged member being disposed at an angle to said marginal flange, spaced arms respectively secured to said door and projecting outwardly beyond said marginal flange, said arms passing beneath and engaging said flanged member, and means movably mounted upon the car body for respectively cooperating with said arms to support the door in closed position.

3. In car door mechanism, the combination with a hinged door provided with a flange, of a flanged member secured to said door in overlapping relation to the flange thereof, said flanged member having a flange extending parallel to said door flange and having another flange disposed parallel and in spaced relation to the plane of said door, an arm secured to said door and projecting outwardly beyond said flanged member, said arm having a plurality of angularly disposed flanges one of which engages the last named flange of said flanged member, and means movably mounted upon the car body

for cooperating with said arm to support said door in closed position.

4. In car door mechanism, the combination with a hinged door provided with a 5 marginal flange, of a flanged member over-lappingly engaging said door flange and rigidly secured to the latter, said flanged member having an inwardly extending portion spaced from the plane of said door, a 10 plurality of arms secured to said door and rigidly connected to the inwardly projecting portion of said flanged member, said arms passing beneath and projecting outwardly beyond said flanged member and said door 15 flange, and means movably mounted upon the car body for respectively cooperating with said arms to support said door in closed position.

5. In car door mechanism, the combination with a hinged door provided with a 20 marginal flange, of a flanged member rigidly secured to said door flange, said flanged member being provided with a portion disposed at an angle to said door flange in 25 spaced relation to the plane of said door, an arm secured to said door and projecting outwardly beyond said door flange, said arm being provided with a flange passing beneath and engaging said flanged member, 30 and means movably mounted upon the car body for cooperating with said arm to support said door in closed position.

6. In car door mechanism, the combination with a hinged door, of door supporting 35 arms secured to said door and projecting beyond an edge thereof, said arms extending at an angle to each other, and means movably mounted upon the car body for cooperating with said arms to support the 40 door in closed position.

7. In car door mechanism, the combination with a hinged door, of a plurality of door supporting arms secured to said door said arms projecting beyond said door and 45 having portions extending obliquely with respect to the hinge axis of said door, and means movably mounted upon the car body for cooperating with said arms to support said door in closed position.

50 8. In car door mechanism, the combination with a hinged door, of a plurality of door supporting arms secured thereto, said arms having portions projecting beyond the free edge of said door opposite the hinge axis thereof and being divergent inwardly, and means movably mounted upon the car body for cooperating with said arms to support said door in closed position.

60 9. In car door mechanism, the combination with a hinged door, of a plurality of door supporting arms secured thereto, said arms projecting beyond the free edge of said door opposite the hinge axis thereof and respectively extending in directions intersecting adjacent edges of said door at ob-

lique angles, said arms being secured to said door adjacent the edges of the latter, and means movably mounted upon the car body for cooperating with said arms to support said door in closed position.

70 10. In car door mechanism, the combination with a hinged door, of a plurality of spaced door supporting arms converging toward each other outwardly from the hinge axis of said door said arms having portions 75 projecting beyond the edge of said door opposite its hinge axis, a door stiffening member secured to said door between said arms and extending at an angle to the latter, and means movably mounted upon the car body 80 for cooperating with said arms to support said door in closed position.

11. In car door mechanism, the combination with a hinged door, of stiffening flanges 85 respectively bordering the side edges of said door, a flanged member rigidly secured to said door adjacent the free edge thereof remote from the hinge axis and angularly disposed with respect to said stiffening flanges, a plurality of door arms terminating at their 90 rear ends adjacent said stiffening flanges and passing beneath and projecting beyond the said flanged member at the free edge of the door, and means movably mounted upon the car body for cooperating with said arms 95 to support said door in closed position.

12. In car door mechanism, the combination with a hinged door provided with a marginal flange, of a flanged member over-lappingly engaging said marginal flange 100 and rigidly secured thereto, flanged door stiffeners connected to said door adjacent respective edges thereof and extending from said flanged member toward the hinge axis of said door, a plurality of door arms secured to said flanged member and said door stiffeners and extending obliquely with respect thereto and projecting outwardly beyond the said marginal flange of the door, and means movably mounted upon the car 110 body for cooperating with said arms to support said door in closed position.

13. In car door mechanism, the combination with a hinged door, of a flanged member secured to said door adjacent the free 115 edge thereof remote from the hinge axis, a plurality of door stiffeners secured to said door between said flanged member and the hinge axis of the door and extending at an angle to said axis, a plurality of door supporting arms secured to said door and passing beneath said flanged member and projecting outwardly beyond said door, said arms having portions extending obliquely with respect to said flanged member and said door stiffeners, and means movably mounted upon the car body for cooperating with said arms to support said door in closed position.

120 14. In car door mechanism, the combination with a hinged door, of a flanged mem- 125

- ber secured to said door adjacent the free edge thereof remote from the hinge axis, flanged door stiffeners secured to said door adjacent the respective edges thereof and 5 extending at an angle to the hinge axis of the door, a plurality of angle iron door arms projecting outwardly beyond the free edge of said door remote from the hinge axis, said arms having portions extending obliquely 10 with respect to said flanged member and said door stiffeners and engaging and being respectively secured to said flanged member and said stiffeners, and means movably mounted upon the car body for cooperating 15 with said arms to support said door in closed position.
15. In car door mechanism, the combination with a hinged door, of a door stiffener secured thereto and extending from a point 20 adjacent the free edge of the door toward its hinge axis, means carried by said door constituting a lever seat adjacent the outer end of said door stiffener, a plurality of means for supporting said door in closed
- position, said last named means being respectively disposed on opposite sides of said door stiffener, and fulcrum means for cooperating with a lever adapted to engage said seat to force said door to closed position. 25
16. In car door mechanism, the combination with a hinged door, of a door stiffener secured thereto in a substantially central position, a plurality of door arms projecting outwardly beyond the free edge of said door, said door arms being disposed upon opposite sides of said door stiffener, a plurality of movable means mounted upon a car body for respectively cooperating with said arms to support said door in closed 30 position, means carried by said door forming a lever seat adjacent the outer end of said door stiffener, and means forming a fulcrum for a lever adapted to engage said seat to force said door to closed position. 35
